C. C. SHIPP.
HEATING AND VENTILATING UNIT.
FILED AUG. 27, 1921.

UNITED STATES PATENT OFFICE.

CLARENCE C. SHIPP, OF INDIANAPOLIS, INDIANA.

HEATING AND VENTILATING UNIT.

Application filed August 27, 1921. Serial No. 496,032.

To all whom it may concern:

Be it known that I, CLARENCE C. SHIPP, a citizen of the United States, residing at Indianapolis, in the county of Marion and 5 State of Indiana, have invented new and useful Improvements in Heating and Ventilating Units, of which the following is a specification.

This invention relates to ventilating apparatus for steam heated houses wherein radiators either wholly or partially encased draw their supply of air from without the building through boxes located in the walls of the rooms.

15 I have previously used a wall-box and a tubular conduit extending horizontally therefrom to the base of the ventilator, but the wooden strip required in the conduit for nailing the assembled parts together has restricted 20 the cross sectional area of the conduit, thereby reducing its air-supplying capacity, and the air, by being delivered to the radiator casings in straight lines, has no contacting surface to beat against and break its force 25 and to prevent the carrying in of rain, snow and dust.

The object of this invention is to provide ample room for a ventilator box and for a tubular conduit of unrestricted capacity; 30 and a further object is to deflect the current of air from a straight line and to contact it with a surface at such an angle to the initial flow as to retard the elements carried in by it, and deliver the air into the 35 radiator casing in a more quiet and neutral condition than heretofore.

I accomplish the above, and other objects which will hereinafter appear, by the mechanism illustrated in the accompanying 40 drawing, in which:

Fig. 1 is a vertical section of the wall and floor of a room with my invention in perspective and vertical section assembled therein operatively with an incased radiator. This figure shows the damper which 45 controls the supply of air, and its operating mechanism, in closed position of the damper. Fig. 2 is a detail in vertical section of the mechanism shown in Fig. 1, 50 with the damper in full open position, and Fig. 3 is a section on the line 3—3 of Fig. 2 showing the metal fold on which the ends of the damper rest when closed.

Like characters of reference indicate like 55 parts in the several views of the drawing.

The radiator sections 4 may be and are of any usual and suitable construction, to which steam is supplied in the usual manner for the radiation of heat to heat the room in which the sections are placed. The 60 radiator sections are wholly or partially enclosed by a sheet metal casing 5, usually supported upon a cast-iron base 6. The above parts are assembled near a wall 7 of a building of which the room to be heated is a part. For sanitary reasons it is desirable to create a circulation of air in the heated room, provide the latter with a ventilator (not shown) at the top for the discharge to atmosphere of foul air, and 65 to draw in air from the outside of the building to take the place of the air discharged thereby producing a circulation in which pure air is substituted for impure air. This is accomplished by connecting a suitable 70 opening in base 6, on the side next to the adjacent wall of the room, with a vertical air-chute 8, by means of a suitable sleeve, here shown as in two telescoping sections 9 and 10, to allow for any adjustment in distance between the radiator casing and chute, 75 caused by variations in the thickness of wall 7 or the distance which the radiator is set from said wall. A wooden header 11 is placed above the telescoping sleeve, in 80 the wall, to be used as a nailing-strip for the attachment of the sleeve and chute. The vertical extension of the sleeve 8 and its cross sectional area will depend upon the requirements and condition of the installation, but it will be sufficiently long to change 85 the flow of air from direct to indirect flow and to provide a wall 12 as a baffle plate for the air to beat against for the removal of snow and rain and the dislodgement of 90 dust particles. The chute 8 connects with the bottom of a wall-box 13, the outer member of which is preferably made out of cast iron with the usual storm louvers 14. It will also have the usual wire insect screen 100 15, and the discharge through the wall-box into the vertical chute 8 will be regulated and controlled by a damper 16, having one edge hinged at 17 to the wall 12 of the chute 8, and extending thence downwardly and 105 obliquely across the chute 8, with a bearing at its lower opposite edge upon the bottom of the wall-box in the manner shown. The ends of the chute 8, like the sides of said chute, are preferably formed out of sheet 110

metal and will have flanges 19 bent therefrom in the manner shown in Fig. 3 and in turned obliquely as rests for the ends of the damper 16 when the damper is in its closed position.

The damper 16 has a pair of under-side ears to which the upper end of an operating bar 20 is hinged. The lower end of the bar 20 is hinged to an arm of a T-shaped lever 21, the stem of which is hinged to ears 30 attached to the bottom of plate 12. A foot-bar 22 has one end hinged to the opposite arm of the T-shaped lever from that to which the bar 20 is hinged, and the opposite 10 end of the foot-bar 22 is extended through a suitable slot 23 in the front of box-base 6, and is sufficiently continued to afford suitable length for manipulation by the foot of a person desiring to change the position of 15 the damper. The end of foot-bar 22 projecting in front of base plate 6 is provided with a plurality of notches 24 in its upper edge for engagement with the plate 6 in the manner shown in Fig. 2 to hold a given adjustment of the damper 16. The foot-bar 22 will 20 preferably be in two lapped parts, one of which is longitudinally slotted and the other provided with bolts through said slot, whereby the length of the foot-bar may be changed 25 to fit the location of the box-base 6 in its distance from the chute 8. Connection between the opening in the rear of base 6 and the two-part sleeve comprising members 9 and 10 is by a sleeve 25 having a vertical 30 wall-flange 26. The position of the radiator casing is retained by nailing a wooden quarter-round 27 to the floor of the room 28 against the rear box-base 6.

In the operation of my invention, the adjustable sleeve members 9 and 10 and adjustable foot-bar 22 provide means for setting the parts to fit the location of the chute 8 in the wall and the distance of the radiator 4 from the wall. The carrying of the chute 45 8 up vertically to a considerable distance above the sleeve connection with the radiator-casing makes a bend in the air-inlet which prevents a direct draft or current of air from the outside to the radiator-casing, 50 eliminates snow and rain and dust to a large extent, but, moreover, it provides for connecting with the bottom of the radiator-box, instead of the end of the box, and thereby allows for the use of a much larger chute 55 in cross-sectional area than would be permitted otherwise; and by placing the damper obliquely across the chute in the box ample room for the swing of the damper is obtained and a substantial bearing on the bottom of the box is provided for the damper when closed.

In the opening and closing of the damper the foot-bar 22 is readily adjusted by a pressure of the operator's foot and a given adjustment is held by the engagement of a

side of one of the notches with the wall of the base 6, the weight of the damper serving to hold the adjustment until the foot-bar is released by a downward pressure on its outer end which lowers the upper edge of 70 the bar and its notch out of contact with base 6.

A pin 31 in the foot-bar 22 holds the bar from moving endwise too far through the 75 box-base 6.

The damper 16 in open position prevents the formation of a dead air pocket in the corner above it and starts the air downwardly into the chute 8.

While I have described and shown the best form of my invention now known to me, it is obvious that changes may be made in the position of the wall-box and the construction and operation of the damper, and other matters and I therefore do not desire to be limited unduly, or any more than is required by the appended claims, and what I claim is:—

1. The combination, with a radiator, and a radiator casing, of a wall-box for the admission of air, a chute having a vertical portion into which the wall-box discharges, a sleeve adjustable in its length connecting the chute with the casing, damper means for regulating the air admission and a damper-controlling means locked by the weight of 95 the damper and manually released.

2. The combination, with a radiator, and a radiator casing, of a wall-box for the admission of air, a chute having a vertical portion connecting with the bottom of the wall-box and discharging into the bottom of the radiator casing, damper means at the junction of the chute and wall-box, and damper operating means comprising a foot-bar pivoted at its inner end to the damper, and means operated by the weight of the damper 105 acting on the foot-bar to lock the outer end of the foot-bar.

3. The combination, with a radiator, and a radiator casing, of a wall-box for the admission of air, a chute having a vertical portion connecting with the bottom of the wall-box, a sleeve adjustable in its length between the chute and the bottom of the radiator casing, damper means at the junction of 115 the chute and wall-box, and means adjustable in its length for manually operating the damper.

4. The combination, with a radiator, and a radiator casing, of a wall-box for the admission of air, a chute having a vertical portion connecting with the bottom of the wall-box, a sleeve adjustable in its length between the chute and the bottom of the radiator casing, damper means at the junction of 120 the chute and wall-box, and means for manually operating the damper comprising a foot-bar in a plurality of parts which parts are adjustable to vary the length of the bar.

5. The combination, with a radiator, and 130

- a radiator casing, of a well-box located above the floor-level on which the radiator stands, a vertical chute extending from the bottom of the box and having a horizontal lower portion discharging into the radiator casing at the base of the casing, a damper at the base of the wall box and top of the chute, and means for adjusting the length of said horizontal lower chute portion.
- 10 6. The combination, with a radiator, and a radiator casing, of a wall-box located above the floor-level on which the radiator stands, a vertical chute extending from the bottom of the box and having a horizontal lower portion discharging into the radiator casing at the base of the casing, means for adjusting the length of said horizontal lower chute portion, a damper at the junction of the wall-box and chute, and lever and connecting-bar means connected with the damper and terminating outside in front of the radiator casing.
- 15 7. The combination, with a radiator, and a radiator casing, of a wall-box located above the floor-level on which the radiator stands, a vertical chute extending from the bottom of
- the box and having a horizontal lower portion discharging into the radiator casing at the base of the casing, means for adjusting the length of said horizontal lower chute 30 portion, a damper hinged at the junction of the wall-box and chute, a T-shaped lever pivoted in the chute at the elbow between the vertical and horizontal members of the chute, an operating bar connecting the 35 damper and T-shaped lever, a foot-bar extending outside of the radiator casing from the T-shaped lever, and means for holding an adjustment of the foot-bar.
8. The combination, with a wall-box for 40 supplying air to steam radiators, of a chute formed out of sheet metal connected therewith, said chute having an elbow near the box, a hinged damper-plate in the chute at the elbow, and supports for the ends of the 45 damper-plate in closed position formed by bending the sheet metal of the chute inwardly of the chute upon itself to form a flange.

Signed at Indianapolis, Indiana, this the 50
24th day of August, 1921.

CLARENCE C. SHIPP.
